Inventor:

August J. Mottlau,
By his Atty, T. W. Richards.

UNITED STATES PATENT OFFICE.

AUGUST J. MOTTLAU, OF JENKINTOWN, PENNSYLVANIA, ASSIGNOR TO A. MECKY COMPANY, OF PHILADELPHIA, PENNSYLVANIA, A CORPORATION OF PENNSYLVANIA.

HEATING-UNIT SUPPORT FOR TOASTERS.

Application filed January 16, 1923. Serial No. 613,017.

To all whom it may concern:

Be it known that I, AUGUST J. MOTTLAU, a subject of the King of Denmark, residing in Jenkintown, in the county of Montgomery and State of Pennsylvania, have invented certain new and useful Improvements in Heating-Unit Supports for Toasters, of which the following is a specification.

This invention relates to electric heaters or toasters and particularly to improvements in the toasters shown in the United States application of Alice Lee Mottlau, filed September 29, 1920, Serial No. 413,515 for duplex toasters, and the United States application of August J. Mottlau, filed February 17, 1922, Serial No. 537,289, for electric cookers and toasters; though it is noted that the invention is not limited to toasters, nor in some respects even to electrical devices.

One object of the invention is to provide, in an apparatus or device of this kind, easily and conveniently removable and replaceable heating unit supports.

Other objects of the invention are to provide, in an apparatus or device of this kind, efficient arrangements of mounting and connecting the heating unit supports.

Other objects of the invention are to improve generally the simplicity and efficiency of such devices and to provide a device or apparatus of this kind which is durable, economical to manufacture and operate and which will not get out of order.

For the accomplishment of these and other objects my inventions are embodied in an improved toaster or heater which, briefly stated, comprises a base which has oppositely mounted standards thereon, each standard carrying a heating unit mounting consisting of an insulating support provided with a plug receiving end and an enlarged outer end. A conductor connecting block received in said enlarged end carries on its inner side contact springs; and a contact plug inserted into said plug receiving end.

Other objects of the invention will appear as the description proceeds; and while herein details of the invention are described, the invention is not limited to these, since many and various changes may be made without departing from the scope of the invention as claimed.

In the accompanying drawing, showing

by way of example one of many possible embodiments of the invention, Figure 1 is a front elevation of my electric heater or toaster, showing one half in axial section;

Fig. 2 is an axial vertical sectional view of the mounting, showing the heating unit core in elevation;

Fig. 3 is an outer end view of the mounting;

Fig. 4 is an inner end view of the mounting with parts removed;

Fig. 5 is a front view of the block, showing the contact springs;

Fig. 6 is a sectional view taken on line 6—6 of Fig. 5; and

Figs. 7 and 8 are, respectively, inside elevation and vertical sectional view of the contact plug.

Referring to the drawings, Fig. 1, my toaster is shown as comprising a disk base 10 having an outwardly and downwardly extending flange 11 forming a space 12 under said base, and provided with passages 13 therethrough at opposite points. Legs 15 are attached to the under side of base 10 supporting it in horizontal position. Outwardly and upwardly extending hollow standards 16 are oppositely mounted on the flange 11 and communicate with space 12, one of said standards having a conductor opening 17. The upper inner wall of each standard is provided with a large support opening 20, and the outer wall with a perforation 21 opposite the lower part of the support opening 20.

An insulating heat unit support 25 is received in the opening 20, comprising an upper inwardly pointing socket 26 having interior oppositely positioned arcuate retaining lugs 27 at its inner end providing arcuate passageways 30 therebetween, and also having an interiorly enlarged outer end 32 provided at the lower part with a positioning seat 33 communicating therewith. One of lugs 27 has an interiorly projecting stop portion 31. Support 25 has at its lower portion a countersunk opening 35 registering with said perforation 21, and vertical parallel channels 36 on its outer face. A handle 38 having an internally threaded recess 39 in its inner end is attached to the outer side of said standard by means of a screw 37 passing through the base opening 35, outer wall perforation 21, and into said threaded

recess 39 to securely hold support 25, standard 16 and handle 38 in assembled position.

Mounted in the enlarged end 32 of support 25 is an insulating conductor connection block 40, Figs. 2 and 6, which is provided with two passages 41 therethrough, countersunk as at 42, Fig. 6, from the outer side, and also has channels 43 from said 10 countersunk passage ends 42 communicating with base portion channels 36. A lug 44, Fig. 5, cooperates with the seat 33 to maintain said block 40 against rotation in support 25. Connecting bolts 45 passing 15 through the block passages 41 have nuts 46 disposed in the countersunk recesses 42; said bolts 45 securing to the inner wall of block 40 flat arcuate connection springs 50 which have free ends extending inwardly and terminating at opposite points adjacent the heads of the bolts 45. Electric conductors 60 passing through said conductor opening 17, through the channels 36 and 43, have their ends connected to the bolts 45 under 20 said nuts 46.

An insulating contact plug 70 having horizontal slots 71 therethrough, has on its inner end laterally extending arcuate locking lugs 72, which are adapted to be inserted through said passages 30 and rotated behind said retaining lugs 27 to form a spring pressure contact with the springs 50. Core supporting conductor arms 80 are passed through the slots 71 and have their 35 inner ends 81 bent at right angles away from each other bearing against springs 50. Plug 70 is provided on its inner face with recesses 75 to permit insertion of a bending tool (not shown) to form contact ends 81. The outer portions 82 of arms 80 are offset 40 away from each other and terminate in a cross portion 83, between which cross portions 83 there is mounted a tubular refractory insulating core 90 having a spiral groove 91 covering its outer surface, and having cross grooves 92 on its ends adapted 45 to receive the arms terminating cross portions 83. Disposed in the groove 91 there is wound an electric heating coil 95, having 50 its ends secured to said crosses 83 of the arms 80.

What I claim is:

1. In a support for a heating unit, in combination, a supporting member having 55 at one end an opening and at its opposite end an enlarged opening communicating with the first opening, opposed retaining means at the outer edge of the first opening having passages therebetween, an insulating 60 conductor connection block located in said enlarged opening, opposed contact members secured to said block and underlying said opposed retaining means, means for connecting said contact members to a source of 65 electricity, an insulating contact plug re-

ceived in the passages between the opposed retaining means and extending into the first opening and provided with means engageable with said retaining means by partial rotation of the plug for retaining the plug 70 in the first opening and having passages through the plug, and electrically conductive supporting means for a heating unit insertible in the last mentioned passages and contactible with said contact members when 75 said plug is partially rotated.

2. In a support for a heating unit, in combination, a supporting member having at one end an opening provided at its outer edge with opposed inturned retaining lugs 80 having passages between the adjacent ends of the opposed lugs and having at the opposite end of said member an enlarged opening communicating with the first opening, an insulating conductor connection 85 block located in said enlarged opening, opposed spring contact members secured to said block and underlying said retaining lugs, means for connecting said springs to a source of electricity, an insulating contact 90 plug received in the passages formed between the ends of the retaining lugs and extending into the first opening and having means for engagement with the inner sides 95 of said lugs by partial rotation of the plug for retaining the plug in the first opening and having passages through the plug, and electrically conductive supporting members for a heating unit insertible in the last mentioned 100 passages and contactible with said contact springs when said plug is partially rotated.

3. In a support for a heating unit, in combination, a supporting member having at one end a circular opening provided with opposed arcuate inturned retaining lugs having arcuate passages between the adjacent ends of the opposed lugs and having at the opposite end of said member an enlarged circular opening communicating with the first opening, an insulating conductor connection block located in said enlarged opening, opposed arcuate flat spring contact members secured to said block and underlying said retaining lugs, means for connecting said springs to a source of electricity, an insulating contact plug received in the passages formed between the ends of the retaining lugs and extending into the first opening and having means for engagement with the inner sides of said lugs by partial rotation of the plug for retaining the plug in the first opening and having passages through the plug, and electrically conductive supporting members for a heating unit insertible in the last mentioned passages and contactible with said contact springs when said plug is partially rotated.

4. In combination, a support having an upper inwardly pointing socket provided

- with interior oppositely positioned arcuate retaining lugs at its inner end forming arcuate passageways therebetween, one of said lugs having an inwardly projecting stop portion; said support having an interiorly enlarged outer end provided at the lower part with a positioning seat communicating therewith; and an insulating plug having on its inner end laterally extending arcuate locking lugs adapted to be inserted through said passageways and rotated behind said retaining lugs to retain said plug in contact position, and provided with bending tool inserting recesses.
5. In combination, a support having an interiorly enlarged end and a channeled base portion; an insulating conductor connection block received in said enlarged end having two passages therethrough countersunk from the outer side, and channels from said countersunk passage ends communicating with said base portion channels, and having a lug cooperating with said seat to maintain said block against rotation in said support; connecting bolts passing through said block passages and having nuts disposed in said countersunk recesses; flat arcuate connection springs having one end secured to the inner side of said block by the heads of said bolts, and having their free ends extending inwardly terminating at opposite points adjacent said bolts; and conductors passing through said channels and having their ends connected to said bolts under said nuts.
6. In combination, a hollow standard having a large support opening and the outer wall having a perforation opposite the lower part of said support opening; and insulating support received in said opening having a base opening; a handle having threaded recess in its inner end; and a screw passing through said base opening, outer wall perforation, and into said threaded recess to securely hold said support, standard and handle in assembled position.
7. In combination, an insulating support having a tubular portion; a block received in one end of said support; contact springs on the inner side of said block; a unit supporting contact plug removably received in the other end of said support to form an enclosed contact chamber; core supporting conducting arms carried by said plug extending into said chamber and bent at right angles away from each other and bearing against said springs; and a heating unit having a coil secured to said arms.
8. In combination, a one piece tubular portion having one end enlarged and a smaller end provided with inwardly projecting retaining lugs forming passageways therebetween; a block received in said enlarged end; connection members secured on the inner face of said block; a one-piece
- plug of insulating material received in said smaller end and provided with opposite lugs adapted to pass through said passageways and to be turned behind said retaining lugs; a pair of conducting arms passing through said plug and engageable with said members; and a unit having a heating coil connected to the arms.
9. In combination, a one piece tubular portion having one end enlarged and the smaller end provided with inwardly projecting retaining lugs forming passageways therebetween and each having a stop at one end of its inner face; connection members secured in said larger end; a plug of insulating material received in said smaller end and provided with opposite lugs adapted to pass through said passageways and to be turned behind said retaining lugs until stopped by the stop; a pair of conducting arms passing through said plug and engageable with said members; and a unit having a heating coil connected to the arms.
10. In combination, a one piece tubular portion having one end enlarged and the smaller end provided with inwardly projecting retaining lugs forming passageways therebetween; a block received in said enlarged end and having passages therethrough; bolts in said passages; flat connection springs secured on the inner face of said block by said bolts; a plug of insulating material received in said smaller end and provided with opposite lugs adapted to pass through said passageways and to be turned behind said retaining lugs; a pair of conducting arms passing through said plug and provided with outwardly turned arms engageable with said springs; and a unit having a heating coil connected to the arms.
11. In combination, a one piece tubular portion having one end provided with inwardly projecting retaining lugs forming passageways therebetween; a block received in the other end; connection springs secured on the inner face of said block; a one-piece plug of insulating material received in said portion and provided with opposite lugs adapted to pass through said passageways and to be turned behind said retaining lugs; each of said opposite lugs having a bending recess in its inner face; a pair of conducting arms passing longitudinally through said plug and provided with outwardly turned arms disposed over said recess and engageable with said springs; and a unit having a heating coil connected to the arms.
12. In combination, a one piece tubular portion having one end enlarged and the smaller end provided with inwardly projecting retaining lugs forming passageways therebetween and each having a stop at one end of its inner face; a block received in

said enlarged end and having passages therethrough; bolts in said passages; connection members secured on the inner face of said block by said bolts; a plug of insulating material received in said smaller end and provided with opposite lugs adapted to pass through said passageways and to be turned behind said retaining lugs; a pair of conducting arms passing through said plug and engageable with said member; and a unit having a heating coil connected to the arms.

13. In combination, a one piece tubular portion having one end provided with in-

wardly projecting retaining lugs forming 15 passageways therebetween; connection members secured in said portion; a one piece plug of insulating material received in said smaller end and provided with opposite lugs adapted to pass through said passageways 20 and to be turned behind said retaining lugs; a pair of conducting arms passing longitudinally through said plug and provided with outwardly turned inner arms engageable with said members; and a unit supported 25 by the outer ends of said arms and having a heating coil connected to the arms.

AUGUST J. MOTTLAU.
